LOCKING MECHANISM FOR BINDERS

Walter E. Schroer, Affton, Mo., Victor Trybinski, Jr.,
East St. Louis, Ill., and Irvin H. Walling, St. Louis,
Mo., assignors to Loose Leaf Metals Company, St.
Louis, Mo., a corporation of Missouri

Application July 16, 1956, Serial No. 598,008

1 Claim. (Cl. 129—13)

The present invention relates to loose leaf binder metals, and more particularly to a novel locking mechanism for binders of the separable type, such as are used in catalogs, manuals and the like.

In brief, the present novel locking mechanism includes a release lever bracket and a lock-case bracket, which are secured to one of two binder members forming a catalog, parts manual, or the like. A release lever is pivotally mounted upon the release lever bracket and is operatively connected, for release of, a lock dog through the medium of a connecting lever pivotally mounted upon the release lever. The lock dog is pivotally disposed within a lock case in operative relation with a lock post secured to the other binder member. The lock case is mounted upon the lock-case bracket. A spring biases the lock dog into biting engagement with the lock post. For separation of the binder members or for relative movement thereof, the lock dog is released through pivotal movement of the release lever.

An object of the present invention is to provide a novel locking mechanism for binders of the separable type which is positive in action in retaining the binder members in selected relative positions, yet which may be readily released for separation or relative movement thereof.

Another object is to provide a novel locking mechanism for binders of the separable type which requires positive release for separation of the binder members, but which permits assembly thereof without the necessity of manual manipulation of the locking mechanism.

Other objects are to provide a novel locking mechanism for binders of the separable type which is simple in construction, which is adapted to function over a long period of time through numerous manipulations without any servicing requirement, which is adapted to function serviceably with heavy catalogs, and the like, for its intended function, and which otherwise fulfills the objects and advantages sought therefor.

The foregoing and other objects and advantages are apparent from the following description taken with the accompanying drawings, in which:

Figure 1 is a plan view of a catalog incorporating the principles of the present invention;

Figure 2 is an end view thereof;

Figure 3 is an enlarged cross-sectional view taken on substantially the line 3—3 of Figure 2;

Figures 4, 5, 6 and 7 are cross-sectional views taken on substantially the lines 4—4, 5—5, 6—6, and 7—7 of Figure 3, Figures 6 and 7 being on a further enlarged scale for clearer illustration of details;

Figure 8 is a view similar to Figure 3, illustrating the locking mechanism in release position and the separable members of the binder in partially released released relation;

Figure 9 is a cross-sectional view on substantially the line 9—9 of Figure 8, on the further enlarged scale of Figures 6 and 7;

Figures 10 and 11 are enlarged cross-sectional views

2

taken on substantially the lines 10—10 and 11—11 of Figure 8;

Figure 12 is a cross-sectional view taken on substantially the line 12—12 of Figure 11;

Figure 13 is an isometric view of the release lever bracket;

Figure 14 is an isometric view of the lock case; and

Figure 15 is an isometric view of the connecting lever.

Referring to the drawings more particularly by reference numerals, 20 indicates generally a locking mechanism incorporating the teachings of the present invention illustrated as operatively mounted in a separable catalog binder generally designated 22.

The catalog 22 is of standard form and includes a top 15 binder member 24 and a bottom binder member 26, the former of which has secured thereto guide members 27 for the sliding reception of the latter member, as is clear from the drawings and as is well known. Sheet retaining posts 28 are secured to the binder member 26. A 20 posting bar 30 has secured thereto sheet-receiving posts 31 and pins 32 which enter suitable apertures 34 in the binder member 24.

The locking mechanism 20 comprises a lever case bracket 35 secured by rivets 36 to the binder member 24, 25 as is clear from Figures 8 and 9. A release lever bracket 37 is welded or otherwise secured to the lock-case bracket 35 transversely thereof and adjacent the rivets 36. The release lever bracket includes a stop flange 38 (Fig. 13).

A release lever 40 is pivotally mounted on the release 30 lever bracket by a rivet 41 and is disposed to engage the stop flange 38 in one extreme position of movement thereof (Figs. 3, 4 and 8). The release lever includes a thumb flange 42 and an interiorly located U-portion 43. A connecting lever 45 is pivotally connected to the bight 35 of the U-portion 43 by a rivet 46. At its free end, the connecting lever 45 has a T-head 47 (Fig. 15).

A lock case 50 (Fig. 14) is mounted upon the free end of the lock-case bracket 35 by means of integral tabs 51 which extend through suitable openings in the lock-case bracket 35 and are peened over to secure the lock case 50 firmly in place. At each end of the lock case 50 is an elongated pivotal slot 52; along the juncture of one side and the top is an elongated slot 63; and aligned annular openings 54 are in the opposed sides.

As is clear from Figures 10—12, a lock dog 58 is disposed within the lock case 50 and includes an integral tab 59 disposed in each slot 52 to permit pivotal movement. Centrally of the lock dog 58 is an aperture 60 which is in alignment with and of the same size as the openings 54. At one end is a tab 61 having a flange portion 62 which extends into the end of a coil spring 64 mounted in the lock case 50 (Fig. 12), which biases the lock dog 58 about the axis of the pivot tabs 59. A U-shaped cutaway 66 of about the width of the elongated slot 53 is formed in the edge of the side of the lock dog 58 remote from the pivot tabs 59.

The connecting lever 45 extends through the elongated slot 53 and through the cutaway 66, and has the T-head 47 in engagement with the lock dog 58. The relationship between the release lever 40, the connecting lever 45, and the lock dog 58 is such that the horizontal position of the release lever 40, as illustrated in Figure 8, effects a position of the lock dog parallel with the top of the lock case 50.

A lock post 70 is mounted on the binder member 26 and extends through the openings 54 in the lock case 50 and through the aperture 60 in the lock dog 58 (Figs. 7 and 9—12). Under influence of the spring 64, the lock dog 58 normally maintains a biting engagement with the lock post 70 to maintain the binder members 24 and 26 in the selected relationship. When the lock dog 58 is moved to the position parallel with the top of the lock

case 50, the lock post 70 is free and the binder members 24 and 26 may be fully or partially separated as desired. Since the biting engagement of the lock dog 58 is a one-directional engagement, the lock post 70 may be reinserted through the opening 60 without the requirement of manual manipulation of the lock dog 58 through the release lever 40.

It is manifest from the foregoing that to release the lock dog 58, it is but necessary to depress the release lever 40 to the position of Figure 8, whereupon the binder members 24 and 26 may be separated. Once the release lever 40 is freed, the spring 64 will quickly return the lock dog 58 into biting engagement with the lock post 70 to secure the binder members 24 and 26 in the selected positions of movement, such as that of Figure 8.

It is manifest that there has been provided a novel locking mechanism for separable binders, which fulfills the object and advantages sought therefor.

It is to be understood that the foregoing description and the accompanying drawings have been given by way of illustration and example. It is also to be understood that changes in form of the elements, rearrangement of parts, and substitution of equivalent elements, which will be obvious to those skilled in the art, are contemplated as within the scope of the present invention which is limited only by the claim which follows.

What is claimed is:

In combination, a binder metal having two relatively movable members, and a locking device releasably maintaining said movable members in selected relation com-
